APPARATUS FOR EXTRACTING HEAT FROM
GASES UNDER PRESSURELeonard J. Marshall, Anderson, Tenn., assignor to
Combustion Engineering-Superheater, Inc., a
corporation of Delaware

Application July 2, 1947, Serial No. 758,503

3 Claims. (Cl. 122—7)

1

This invention relates to heat exchangers in which the heat is extracted from hot gases under pressure, and it has special reference to such exchangers wherein the extracted heat is employed for purposes such as the generation of steam.

An important object of the invention is the provision of a heat exchanger which is resistant to substantial internal pressure by the gases from which the heat is to be extracted and in which the gas pressure resisting shell is maintained at substantially the lowest temperature of the gases leaving the heat absorbing surfaces.

Another object is to facilitate the manufacture and assembly of such heat exchangers.

Further objects will appear from the following description of an illustrative embodiment of the invention when taken in conjunction with the accompanying drawings wherein:

Figure 1 is a vertical cross section of the improved heat exchanger taken on line 1—1 of Figures 2 and 3;

Figure 2 is a horizontal cross section of the same apparatus taken on line 2—2 of Figure 1;

Figure 3 is a view in front elevation showing the improved heat exchanger used as a steam boiler and indicating piping connections from heat-receiving elements in the exchanger to a steam and water separating drum and to water circulation pumps; and

Figure 4 is a side elevation of the same exchanger-boiler apparatus, as viewed from the right of Fig. 3, showing further piping connection details.

The improved heat exchanger here illustrated comprises an upright shell 1 having top and bottom heads 2 and 3 capable of resisting the internal pressure under which the heating gases flowing therethrough are delivered. In one application for which the disclosed apparatus has been designed, this delivery pressure is about ten atmospheres (approximately 142 pounds per square inch) and the entering gases have a temperature of the order of 1400° F. An inlet 4 for the heating gases is provided in the top head 2 and a gas conduit 5, which forms a seal with the top head around the juncture of inlet 4, with the head extending downwardly through the shell 1.

In this disclosure the inner gas conduit 5 is rectangular in cross section and its cross sectional area is less than that of the surrounding outer casing or shell 1 (see Fig. 2). This inner conduit 5 terminates with its bottom end 6 at a spaced distance from the bottom head 3, there-

2

by providing a gas passage from conduit 5 into space 7 that radially separates the conduit from the outer shell or casing 1. A gas outlet 8 is provided in that outer shell 1 adjacent the top head 2 and beneath the inlet 4. Hot gases under pressure enter the inlet 4, pass downwardly through inner conduit 5, then flow around the bottom end 6 of the conduit into space 7 between the outer shell 1 and conduit 5 and thence upwardly through the space 7 and out of the exchanger casing through side outlet 8.

Heat absorbing surface such as groups or bundles of tubes 9, 10, 11 and 12 are placed within the conduit 5 to absorb heat from the gases flowing thereover and conduct it to fluid that is passed through the tubes. In the illustrative disclosure there are four such bundles of tubes 9—10—11—12, although a different number may be used. Each tube group or bundle 15 is here shown as comprising a multiplicity of parallel rows of tubes 13 bent back and forth transversely of the surrounding conduit 5 to form the represented coils. The opposing tube ends in each of these bundles are connected into an inlet header 14 and into an outlet header 15 for respective supply and removal of a heat absorbing fluid which is passed through the tubes. Preferably the exchanger's inner casing or conduit 5 is made up of a multiplicity of sections 20

16, 17, 18 and 19 equal in number to the number of tube bundles 9—10—11—12. These several sections are joined one to another in end-to-end relation by expansion joints 20. In each of the bundles here designated 9—10—11—12 tube sheets shown at 21 in Figs. 1 and 2 are placed at the bent portions 22 of the fluid-circulating tubes 13 and are provided with holes for receiving those bent portions 22 thereby maintaining proper relative spacing of the individual tubes 13 in the bundle. Each pair of these tube sheets 21 extends above and below the supported tube bundle (9, 10, 11 or 12) to the expansion joints 20 at the top and bottom of the associated conduit section (19, 18, 17 or 16). Each sheet 21 is then bent to contact the exchanger's inner casing or conduit 5 and form a seal with the wall of that casing. In this manner these tube sheets 21 also serve as baffles to keep the gases from short circuiting past the tube ends 22 where the resistance to flow is relatively low.

Each of the tube bundle and casing section assemblages 9—19, 10—18, 11—17 and 12—16 thus formed is supportedly positioned in the exchanger's outer casing 1 through the medium of 55 the assemblage's inlet and outlet headers 14 and

15. Thus, in the case of assemblage 11-17 the tube bundle 11, tube sheets 21 and the surrounding section 17 of the exchanger's inner casing 5 all derive their support from outer casing 1 through the inlet and outlet headers 14 and 15 for that assemblage.

As is best indicated by Fig. 2, each and every header 14 and 15 in the heat exchanger is closed at one end 23 within the shell 1 and extends through the opposite shell side at 24 adjacent the header's other end. The closed end 23 of each header is supported from the shell 1 as by a bracket 25 and each header is further supported by the shell where it passes therethrough at 24. At each point 24, moreover, there is provided means for hermetically sealing the joint between the header and the shell.

Each of the various conduit sections 19, 18, 17 and 16 together with its associated tube bundles 9, 10, 11 and 12 and set of headers 14-15 thus forms a unit which may be completely assembled, welded and stress relieved in the fabricating shop. When, moreover, the heat exchanger is completely assembled the entire weight of each of these component assemblages 9-19, 19-18, 11-17 and 12-16 will be carried by the outer shell through headers 14-15 in the unique manner just explained.

In the embodiment of Figs. 3 and 4, where the heat exchanger is to be used as a steam generator, the uppermost tube bundle 9 serves as a steaming unit, the next lower tube bundle 10 serves as a superheater unit, the next lower tube bundle 11 serves as a steaming unit and the lowermost tube bundle 12 serves as an economizer unit. When so used as a steam generator, a steam and water separating drum 26 is provided into which both of the steaming units 9 and 11 discharge. Preferably these steaming units (first and third counting from the exchanger top) will be provided with forced circulation pumps 27, as represented in Figs. 3 and 4.

In the complete system of Figs. 3 and 4, down-comer tubes 28 connect the bottom of the steam and water separating drum 26 with the suction side of pumps 27; other tubes 29 and 30 connect the inlet headers 14 for the exchanger's steaming units 11 and 9 respectively, with the discharge side of the pumps; riser tubes 31 and 32 respectively connect the outlet headers 15 of the exchanger steaming units 11 and 9 with the steam and water separating drum 26; and a saturated steam tube 33 connects the steam and water drum with the inlet header 14 of the superheater unit 10. The outlet header 15 of this superheater unit 10 is connected by piping to the point of use. The economizer unit 12 receives water from the boiler feed pump (not shown) via pipe 34 connected to its inlet header 14. The economizer outlet header 15 is connected by pipe 35 to the steam and water separating drum 26. Circulation pumps 27 are driven by any suitable means, such as motors 36.

In operation, the hot gases from which the heat is to be extracted enter the heat exchanger through inlet 4 and thence pass downwardly successively through tube bundles 9, 10, 11 and 12 while giving up heat. Upon leaving the economizer unit tube bundle 12 the gases are cooled to their final low temperature and the cool gases thence pass upwardly through the space 7 between the outer shell or casing 1 and the inner conduit or casing 5 to leave the heat exchanger through outlet 8. In this manner the outer shell 1 is exposed only to gases at their final low tem-

perature and the shell temperature approaches that of the cooled gases.

This is an advantage in that the strength of the metal in the shell 1, due to increase in temperature, is impaired as little as possible. Moreover, any minor leakage through the walls or joints of inner conduit 5 into the surrounding space 7 between outer shell 1 and conduit 5 will have but a negligible influence upon the temperature of the relatively large mass of cool gases passing upwardly through said space when mixing therewith.

15 The economizer tube bundle 12 and the steaming tube bundles 11 and 9 are arranged with their inlet headers at the bottom and their discharge headers at the top. For the steaming units this may be of importance in case of failure of the circulating pumps, because water will then flow by natural circulation, from the steam and water drum through the pump, which will be of the centrifugal type, thence through the steaming units and back to the drum. This circulation will be sufficient to protect the tubes of the steaming unit against overheating.

20 25 While the preferred embodiment of the invention has been shown and described, it will be understood that changes in construction, combination and arrangement of parts may be made without departing from the spirit and scope of 30 the invention as claimed.

I claim:

1. A heat exchanger for extracting heat from hot gases flowing therethrough under pressure comprising a vessel having a cylindrical shell and heads capable of resisting the gas pressure internally together with an inlet for the hot gases in one head and an outlet for the cooled gases in the shell adjacent said inlet head; a multi-section gas conduit within the shell extending longitudinally thereof in radially spaced relation thereto and being open at one of its ends and joined at its other end to said inlet head thereby forming a connection with the gas inlet, said multi-section conduit extending through the shell continuously from the inlet head thereof to a location spaced from the opposite shell head whereby to provide a gas passage leading from the open conduit end into the space radially separating the conduit and shell, the sections of 40 the conduit being joined transversely of the conduit by transverse expansion joints; a bundle of heat absorbing tubes within each of said sections made up of rows of tubes bent back and forth; an inlet and an outlet header for each of said 45 tube bundles respectively receiving opposing ends of the heat absorbing tubes in the bundle rows and constituting mechanical supports for those tubes, each of said inlet and outlet headers passing through opposite sides of the respective conduit section, each header being closed at one end and passing adjacent its opposite open end through the wall of said vessel shell to the exterior thereof; means supporting each header from the shell interior at the header's closed 60 end; and means at the point of passage of each header's opposite end through the shell wall further supporting that header from the wall and sealing it with respect thereto.

2. In a heat exchanger for extracting heat 65 from hot gases flowing therethrough under pressure, the combination of a vessel having a cylindrical shell and heads capable of resisting the gas pressure internally together with an inlet for the hot gases in one head and an outlet for 70 the cooled gases in the shell adjacent said inlet

head; a multi-section gas conduit within the shell extending longitudinally thereof in radially spaced relation thereto and being open at one of its ends and joined at its other end to said inlet head thereby forming a connection with the gas inlet, said multi-section conduit extending through the shell continuously from the inlet head thereof to a location spaced from the opposite shell head whereby to provide a gas passage leading from the open conduit end into the space radially separating the conduit and shell; transverse expansion joints securing said sections of the conduit one to another in end-to-end relation; a bundle of heat absorbing tubes within each of said sections made up of rows of tubes bent back and forth transversely of the conduit; an inlet header and an outlet header for each of said tube bundles respectively receiving opposing ends of the heat absorbing tubes in the bundle rows and constituting mechanical supports for the tubes, said inlet and outlet headers being located respectively below and above the supported bundle and projecting through opposite sides of the respective conduit section, each header being closed at one end and passing adjacent its opposite open end through the wall of said drum shell to the exterior thereof; means supporting each header from the shell interior at the header's closed end; means fastening the opposite end of each header in sealed relation to the shell at the point of passage through the shell wall; a steam and water separating drum external to said heat-exchanger shell and having a steam offtake; means connecting said separator drum with the outlet headers of said tube bundles in the heat-exchanger; a circulation pump connected at its suction side with the bottom of said separator drum and at its discharge side with the inlet headers of the tube bundles; and means for driving said pump.

3. In boiler apparatus for generating steam from hot gases flowing therethrough under pressure, the combination of a heat-exchanger having a cylindrical shell and heads capable of resisting the gas pressure internally together with an inlet for the hot gases in one head and an outlet for the cooled gases in the shell adjacent said inlet head; a multi-section gas conduit within the shell extending longitudinally thereof in radially spaced relation thereto and being open at one of its ends and joined at its other end to said inlet head thereby forming a connection with the gas inlet, said multi-section conduit extending from the inlet head through the shell and terminating at a spaced distance from the opposite shell head to provide a gas passage from the conduit's open end into the space radially separating the conduit and shell; transverse expansion joints securing said sections of the conduit one to another in end-to-end relation; a bundle of heat absorbing tubes within each of said sections made up of rows of tubes bent back and forth transversely of the conduit; an inlet header and an outlet header for each of said tube bundles respectively receiving opposing ends of the heat absorbing tubes in the bundle rows and constituting mechanical supports for the tubes, said inlet and outlet headers being located respectively below and above the supported bundle and projecting through opposite sides of the respective conduit section, each header being closed at one end and passing adjacent its opposite open end through the wall of said drum shell to the exterior thereof; means supporting each header from the shell interior at the header's closed end; means fastening the opposite end of each header in sealed relation to the shell at the point of passage through the shell wall; a steam and water separating drum external to said heat-exchanger shell and having a steam offtake; means connecting said separator drum with the outlet headers of said tube bundles in the heat-exchanger; a circulation pump connected at its suction side with the bottom of said separator drum and at its discharge side with the inlet headers of the tube bundles; and means for driving said pump.
